UNITED STATES PATENT OFFICE.

PETER L. HOFFMAN, OF AURORA, ILLINOIS, ASSIGNOR TO RICHARDS-WILCOX MANUFACTURING COMPANY, OF AURORA, ILLINOIS, A CORPORATION OF ILLINOIS.

DOOR-HANGER.

1,120,197.

Specification of Letters Patent.

Patented Dec. 8, 1914.

Application filed May 31, 1913. Serial No. 770,826.

To all whom it may concern:

Be it known that I, PETER L. HOFFMAN, citizen of the United States, residing at Aurora, in the county of Kane and State of Illinois, have invented certain new and useful Improvements in Door-Hangers, of which the following is a specification.

This invention relates to improvements in door hangers adapted to travel on tubular track and to support heavy doors such as are commonly used in freight depots, warehouses, &c., and of the type that may be adjusted both vertically and laterally without disconnecting any of the hanger members.

15 The especial object of the improvements upon which I ask a patent in this case, is to provide a hanger of exceptional strength, made of cast iron, and in which the load or weight carried thereby will be so well distributed as to subject no one part to undue stress or danger of breakage.

20 A further object of my improvements is to provide effective, readily accessible and operable adjusting means of economical construction.

25 Other objects of general utility are attained by my improvements all of which will be apparent to those skilled in the art from an examination of the accompanying drawings which form a part of this application, in which:—

30 Figure 1 is a front elevation of my improved hanger complete; Fig. 2 is a side or edge view of the complete hanger; Fig. 3 is a front elevation of the main lower frame casting; Fig. 4 is a front elevation of the upper frame or wheel housing member; Fig. 5 is a vertical section on the line 5—5 of Fig. 4; Fig. 6 is a side or edge view of the middle member which serves as an adjustable coupling for the upper and lower members; Fig. 7 is a front elevation of the middle member of the hanger.

35 Referring to the details of the drawings as disclosed particularly in Figs. 1, 2, 4, and 5, the reference numeral 8 represents generally the upper or wheel-housing member of my improved hanger which consists of a casting formed with a circular hood portion 8^a, which overhangs and incloses the upper portion of the track-wheel 9, the axle 9^a of which, is journaled in the front and rear walls of said housing. The lower portion of the member 8, is formed with downwardly

extending and diverging legs 8^b, in the inner 55 sides of which are transverse grooves 8^d, rectangular in cross-section. The legs 8^b and the portion of the casting midway therebetween, extend laterally for a substantial distance to form a base, as at 8^c, in which is 60 provided a recess 8^e, which lies below, and in the same vertical plane with, the wheel 9. In the recess 8^e is a horizontal roller 10 having a concave face, and rotatably mounted on an axle-bolt 10^a which extends through 65 the front and rear walls of the extended portion of the frame, as clearly shown in Fig. 5. Extending downwardly from, and longitudinally of the base portion 8^c of the frame 70 8, at one side of its central vertical plane, and in the same horizontal plane with the grooves 8^d, is a rib on one of the vertical sides of which, are teeth which form a rack 8^e for a purpose to be described.

Referring particularly to Figs. 1, 2, and 3, 75 of the drawing, the reference numeral 11 represents generally, the lower hanger frame member or apron, the same consisting of a casting having formed therein three bolt receiving holes 11^a by which the apron is secured to a door, (not shown) and in the upper part of said casting, is a rectangular slot 11^b, on the side margins of which are overhanging flanges 11^c. Midway of the apron, is a transverse outwardly projecting 80 or offset rib 11^d through which is a vertical opening 11^e. The slot 11^b, with its vertical marginal flanges 11^c, provides a slideway for the middle member of my improved hanger shown separately and in detail, in 85 Figs. 6 and 7. This middle member is represented generally by the reference numeral 12, and consists of a casting of the right-angle form shown in Fig. 6, in which transverse horizontal ribs 12^a are formed on the 90 sides of the angular extension 12^b, at the upper end of the casting. In the lower portion of the member 12, are spaced lugs 12^c, between which is arranged the unthreaded portion of a bolt 15, (Fig. 1) the head 15^a 100 of which, rests on the upper edge of said lugs, in a recess formed therefor in said member 12, the walls of said recess engaging the head 15^a and preventing the rotation of the bolt in its bearings. The bolt 15 extends downwardly through the opening 11^e in the lug 11^d, and has its lower portion 105 threaded as at 15^b to receive adjusting and

locking nuts 16, 16^a, respectively. The upper portion of the member 12 is bored longitudinally to receive a bolt 13, the head 13^a of which is toothed to engage the teeth 5 of the rack rib 8^e when the parts are assembled. Near the lower end of the bolt 13, is a hole adapted to be engaged by a suitably pointed device for rotating the bolt when it is desired to adjust the relative position 10 of the members 8 and 11. A set screw 14 engages a hole suitably threaded therefor near the center of the member 12, the inner end of said screw being adapted to impinge upon the lower portion of the bolt 13, 15 and thus prevent the rotation of the latter when the screw 14 is set. The side margins of the member 12 are provided with ribs 12^d which engage the under side of the flanges 11^c of the member 11, thus maintaining 20 the two members 11 and 12 in vertically, slidable relation and preventing lateral movement therebetween.

From the construction described, it will be obvious that the rotation of the toothed head 13^a of the bolt 13 when in engagement 25 with the rack 8^e will cause the wheel housing or upper frame member 8 of the hanger to move inwardly or outwardly relative to the members 11 and 12, and thereby vary the 30 position of the vertical axis of the wheel 9 to the plane of the apron 11 which is bolted to the outer face of the door. When the desired adjustment is effected in this way, the screw 14 is set or tightened, and the 35 members are thereby held against accidental displacement. It will also be obvious that as the connection between the members 11 and 8 is effected by the member 12 through the engagement of the ribs 12^a of the latter 40 with the grooves 8^d of the member 8, and the connection between the members 11 and 12 is effected by the bolt 15, that the rotation of the nuts 16, 16^a, on the bolt 15, will permit the relative movement between the 45 members 11 and 12 in a vertical plane within the limitations of the slideway formed by the flanges 11^c, and that when the proper vertical adjustment is thus effected, the nut 16 may be screwed up tightly against the 50 under side of the lug 11^d, and the lock nut 16^a against the nut 16, and thereby insure the parts against further vertical movement until the nuts are again loosened.

The adjustments of my improved hanger, 55 it will be seen, are effected by the turning of the two bolts, 13 and 15, the former having a head of special or pinion form, and a

non-threaded body, and the latter being of a standard type.

The load carried by my hanger is distributed 60 over the relatively long and strong bearings furnished by the grooved legs 8^b of the member 8, and the ribs 12^a of the member 12, and those bearings are so spread apart as to bring them over the bolts which 65 engage the holes 11^a, thus effectively distributing the weight and tending to prevent any twisting of the hanger on its vertical axis during the movements of the door to which it is connected. It will also be observed 70 that no load is carried by the adjusting bolt 13 so that it may be easily operated to effect the lateral adjustment of the hanger members.

Having thus described my invention what 75 I claim as new and desire to secure by Letters Patent, is:—

1. A door-hanger comprising an upper member having a wheel housing in its upper portion and having a laterally extending 80 base with grooves therein and a rack arranged between said grooves, a lower member having a slideway therein, a middle member horizontally slidable on and supported by the grooved portion of the upper 85 member, and vertically slidable on the lower member, means for relatively adjusting the upper member and middle member through engagement with said rack, and means for relatively adjusting the middle member and 90 the lower member.

2. A door-hanger comprising an upper member, a lower member and a middle member, said middle member supported by and horizontally slidable on the upper member, 95 a rack integral with the upper member, a bolt rotatably arranged in the middle member and having a toothed-head operatively engaging said rack in the upper member, means for locking said bolt against rotation, 100 a slideway connection between said middle and lower members, and means for effecting adjustment between the middle and the lower members, said means comprising a bolt rotatably mounted in the middle member 105 and a nut mounted on said bolt and bearing against said lower member.

In testimony whereof I affix my signature in the presence of two witnesses.

PETER L. HOFFMAN.
